UNITED STATES PATENT OFFICE.

FRANÇOIS EUGÈNE FÉRIER, OF LYON, FRANCE.

DESIGN FOR TEXTILE FABRIC.

44,439.

Specification for Design.

Patented Aug. 5, 1913.

Application filed April 7, 1913. Serial No. 759,549. Term of patent 3½ years.

To all whom it may concern:

Be it known that I, FRANÇOIS EUGÈNE FÉRIER, a citizen of the Republic of France, residing at the city of Lyon, France, have invented a new, original, and ornamental Design for Textile Fabrics, of which the following is a specification, reference being had to the accompanying drawing, forming part thereof.

The figure is a plan view of a piece of fabric showing my design.

I claim:

The ornamental design for a textile fabric, as shown.

FRANÇOIS EUGÈNE FÉRIER.

Witnesses:

FR. PERDRET,
MARIN VACHON.
